UNITED STATES PATENT OFFICE.

CHARLES LANDSHEFT, OF MOUNT JEWETT, PENNSYLVANIA, ASSIGNOR TO CONSOLIDATED MACHINE COMPANY, OF BRADFORD, PENNSYLVANIA.

DEVICE FOR CAPPING OFF GLASS CYLINDERS.

1,163,618.

Specification of Letters Patent.

Patented Dec. 7, 1915.

Application filed August 18, 1914. Serial No. 857,351.

To all whom it may concern:

Be it known that I, CHARLES LANDSHEFT, a citizen of the United States, and resident of Mount Jewett, in the county of McKean and State of Pennsylvania, have invented 5 certain new and useful Improvements in Devices for Capping Off Glass Cylinders; and I do hereby declare the following to be a full, clear, and exact description of the invention, such as will enable others skilled in the art to which it appertains to make and use the same.

My invention relates to an improvement in devices for capping off glass cylinders, 15 the object of the improvement being to provide a device composed of few parts and of such construction that the operation of passing the wire around the glass cylinder and drawing it in snug contact therewith may be 20 readily and safely performed by the operator without handling the wire and thereby subjecting himself to the danger of an electric shock.

With this object in view my invention 25 consists in the construction and combination of parts which will be hereinafter described and pointed out in the claim.

In the accompanying drawings; Figure 1 30 is a view in side elevation of my improvement, illustrating it in its open position and Fig. 2 is a similar view showing it in its closed position, and the electric wire encircling the glass cylinder.

A A¹ represent the two halves of a circle 35 which are preferably formed of aluminum pipe sections, which are hinged together at B, and are insulated from each other.

C C¹ represent the terminals with which the leading-in wires D D¹ are connected.

The free ends of the semi-circular sections 40 A A¹ are provided with insulated handles, E, E¹ and with clamps F F¹ or other suitable supports for the ends of the heating wire G.

One end of the heating wire is permanently 45 secured to the clamp or support F, while the other end of the wire passes around a roller g attached to support F¹ and around the drum of a reel H which is secured to section A¹ of the device and is insulated therefrom.

The device is preferably suspended from an 50 overhead track way by means of a wire H¹ which is insulated from the circular frame A A¹. To insure the alinement of the ends of the heating wire when current is passing 55 through it, one of the clamps or supports F

is provided with a tenon h which enters a socket h¹ in the other clamp F¹, or the tenon and socket or other equivalent means may be attached to the free ends of the semi-circular sections A A¹, it being understood of course 60 that the clamps or supports and tenon and socket are so constructed and made of suitable material to insure the electrical insulation of the two sections at their free ends as well as at their hinged ends.

The operation of the device is as follows:—After a glass cylinder of any length has been placed upon a capping-off horse, the circular support is moved lengthwise of the cylinder to the point at which it is desired to sever the cylinder, and the two hinged sections are opened so as to permit them to be moved laterally above and below the cylinder and then by closing the sections together, the heating wire is caused to encircle the glass cylinder. The handle of the reel is then rotated to cause the heating wire to be brought into snug contact with the cylinder. The circuit is then closed by a suitable switch, not shown, which causes the current to flow from one of the leading-in wires D through section A of the circular frame and from there through clamp F to and through the heating wire G, to clamp F¹ and from thence through the other semi-spherical section A¹ to the other leading-in wire D¹. The electrical resistance of the heating wire G is sufficiently great to cause the wire to be heated to incandescence by the passage of a suitable current through it, and this 70 high degree of heat will enable the cylinder to be capped off on the heated line. The slight space of the cylinder between the two ends of the heating wire may be heated by slightly rotating the circular frame A A¹ 75 while current is passing through the heating wire.

One of the advantages of my improvement is, that it provides a supporting frame for both the leading-in wires and the heating 80 wire, which permits the latter to be passed around the glass cylinder and drawn snugly in contact therewith without requiring the operator to touch the heating wire and hence shields him from the danger of injury due to 85 electric shocks.

It is evident that many changes might be 90 made in the construction and relative arrangement of the parts of my improvement 95 without departing from my invention and 100 105 110

hence I would have it understood that I do not limit myself to the particular construction and arrangement of parts shown and described.

5 Having fully described my invention what I claim as new and desire to secure by Letters-Patent, is:—

10 The combination of a frame consisting of two sections hinged together and each provided at its free end with a handle whereby both handles may be grasped by one hand when the frame is closed around a glass cylinder, a heating wire having one of its ends secured to a terminal at the free end of one

of the hinged sections and engaging a terminal at the free end of the other hinged section, a take up device for the free end of said wire, and a flexible suspension device in which one of said hinged sections has free sliding movement. 15

20 In testimony whereof, I have signed this specification in the presence of two subscribing witnesses.

CHARLES LANDSHEFT.
